UNITED STATES PATENT OFFICE

2,452,835

KNITTED FABRIC AND PROCESS OF
MAKING SAME

Arthur J. Cobert, Greensboro, N. C., assignor to
Burlington Mills Corporation, New Castle
County, Del.

Application October 22, 1945, Serial No. 623,647

2 Claims. (Cl. 66—169)

1

This invention relates to a non-run elastic fabric and method of making the same, and particularly to a knitted fabric of the type made on flat knitting machines wherein certain of the stitches at determined points of location in the knitted fabric are made in the form of locked stitches or knots to render the fabric run-resisting or run-proof.

Heretofore fabrics of the locked-stitch type, made either on circular or flat knitting machines, have been open to the objection that their construction and mode of manufacture reduces the latitudinal stretchability and recoverability of the fabric due to the type of lock-stitch formation used in the fabric. In all prior knitted fabrics of non-run character of which I am aware, it has been the practice to produce the locked stitches by an overlapping of the loops and stretching of the wales where the locked stitches occur, causing a tension or strain in the area of the locked stitches and the formation of a meshy or open-type of fabric, resulting in a reduction in strength and durability of the fabric and a decrease in the elasticity of the fabric below a desirable minimum.

In one well known prior type of fabric having these objections the locked stitch is formed by stretching or spreading the bight portion of a plain loop upon an adjacent needle, which needle also contains a plain loop, and casting these loops in the succeeding course so that the plain loop and partial loop are tied together. As in this construction the spread loop is hung over two wales without releasing another loop, an undesirable tensioning of the fabric in this area is produced and the elasticity of the fabric impaired. In another well known type of fabric of this character some of the loops, particularly the bight portions thereof, are displaced to adjacent loops of adjacent courses, rendering the stitches in that portion of the fabric interlocking, but the loops are so stretched or elongated as to cause an appreciable loss of elasticity in the fabric. The greater the number of locked stitches so formed in a given area in the fabric the greater the loss of elasticity.

One object of my invention is to provide a non-run knitted fabric whereby these objections to prior fabrics are avoided and a fabric produced having perfect locked stitches which do not impair the elasticity, i. e., stretchability and recoverability, of the fabric.

Another object of the invention is to provide a construction and method of manufacture whereby a closely knit, strong and durable and highly elastic knitted fabric may be produced.

Still another object of the invention is to provide a fabric having a novel form of locked stitch whereby security in the tying action is obtained with freedom of motion of the locked portions

2

to allow a maximum degree of elasticity of the fabric.

The accompanying drawing shows a portion of a non-run knit fabric embodying a locked stitch made in accordance with my invention, the loops of the locked stitch being shaded in contrast with the regular loops.

Referring now more particularly to the drawing, A designates a portion of a knitted fabric, in which certain loops are interlocked in accordance with my invention, a, b and c representing three rows or courses of knitted loops. Of the loops in these rows loops 1, 2, 3, 4, 7, 8 and 9 are plain loops of a type well known in the art, but loops 5, 5' and 6 are modified loops of a novel form and arrangement and co-act to produce a locked or tied stitch in this area of the fabric.

In the operation of knitting the fabric, loops 4, 5 and 6 are knit in the conventional manner, but before they are cast from the needles a part 10 of a course loop, such as a leg of loop 5, as shown, which is drawn out to form loop 5', is passed through loop 6, loop 6 is released from its needle and loop 5' impaled on this needle for engagement with loop 3, so that a loop 6' is also formed for engagement with the sinker in the wale between loops 8 and 9 of row c. The loop 5' thus formed has its legs crossed at the point 5^a to provide a lock loop or noose through which the adjacent displaced leg of the loop 5 passes. The process of 20 releasing loop 6 from its needle permits of the formation of loop 5' without any stretching or straining of the thread, because the added length of thread that is added to accomplish this comes partly from loop 5 and partly from loop 6, which latter on its release from its needle becomes very 30 small and feeds a portion of its former length to loop 5'.

It will be seen that the process of forming loop 5' and drawing it through loop 6, releasing loop 6 from its needle and then impaling loop 5' on this needle produces a novel form and arrangement of interlocking or locked stitch in this area of the fabric. If, for example, a break should occur in 40 the fabric which would release loop 2, the unroving action would be stopped at loop 5 because a part of it, namely loop 5', is tied in with loops 5 and 6. It will be noted that in the knitting operation in which this locked stitch is formed there 45 is at no time a multiplicity of stitches upon any one needle, so that all the loops of the fabric will be allowed to relax without any undue stretching or straining in the interlocked area. By locating the locked stitches at proper points in the 50 fabric stoppage of the unroving of the fabric, in case of breakage, beyond an allowable minimum will be ensured.

My improved construction of fabric avoids the 55 production of locked stitches by the process of overlapping or stretching the loops, which causes

a tension or strain in each locked area, reducing the stretch and recoverability, and provides a fabric which retains practically all the elasticity of a plain knit fabric while being of greater strength and better appearance. It will be evident that this improved fabric avoids the production of undue tension in the locked areas because of the character of the interlocking principle involved. While in the process of making the fabric a loop is transferred from one needle to the next, as in most non-run fabrics, an essential difference is that the loop which was originally upon the second needle is permitted to slip through the transferred loop. This slipping through of the loop relaxes the thread taken from the first needle, thereby preserving the original elasticity of the fabric and at the same time forming a perfect lock-stitch. The stitch thus formed presents itself in the form of a tiny knot rather than a large opening in the fabric, so that both the strength and appearance of the fabric are improved, which are features of importance, particularly in the manufacture of gossamer or sheer knit fabrics.

It will be understood that while I have disclosed for exemplification one form of embodiment of my invention, and one way of making the same, changes in the size, shape and arrangement of the parts and the knitting action, such as fall within the scope of the appended claims, may be made without departing from the spirit or sacrificing any of the advantages of the invention.

Having thus described my invention, I claim:

1. The method of producing a lock-loop in a

knitted fabric formed of plain loops and lock-loops, which consists in drawing a partial plain loop of a course through an adjacent plain loop in the same course, releasing the adjacent plain loop from its needle, and impaling the partial plain loop upon this needle.

2. A knitted fabric comprising rows of needle loops and including a loop drawn from a leg of a loop of a row and passing through another loop in the same row adjacent the leg, said drawn loop having its legs crossed and having a loop in the next row and in the same wale as the third-named loop passing therethrough.

ARTHUR J. COBERT.
